WOOD DRILL

Christian L. Schmucker, R.R. 1, Box 177,
Nappanee, Ind. 46550

Filed Mar. 17, 1969, Ser. No. 16,277

Term of patent 14 years

Int. Cl. D8—02; D15—99

U.S. Cl. D54—4

Fig. 1

Fig. 3

Fig. 2

Fig. 4

Fig. 5

FIG. 1 is a perspective view of a wood drill embodying the present design;

FIG. 2 is an elevational view of one side of the drill;

FIG. 3 is an elevational view of the leading end of the drill;

FIG. 4 is a side elevational view; and

FIG. 5 is a cross-sectional view taken on line 5—5 of FIG. 2.

The side and edge opposite those shown in FIGS. 2 and 4 are the same as those shown in the two respective figures.

I claim:

The ornamental design for a wood drill, substantially as shown and described.
